ATTORNEY

UNITED STATES PATENT OFFICE

151,284

DESIGN FOR A JIG-SAW PUZZLE

Richard B. Morris, Quincy, Ill.

Application June 28, 1946, Serial No. 131,115

Term of patent 14 years

(Cl. D34—15)

To all whom it may concern:

Be it known that I, Richard B. Morris, a citizen of the United States of America, residing in Quincy, in the county of Adams, State of Illinois, have invented a new, original, and ornamental Design for a Jig-Saw Puzzle, of which the following is a specification, reference being had to the accompanying drawing, forming a part thereof.

Fig. 1 is a front elevational view of a jig-saw puzzle, showing my new design.

Fig. 2 is an end elevational view, and

Fig. 3 is a rear elevational view of the same.

The design is characterized by being comprised of a plurality of blocks and other independent and separable parts assembled to provide the design shown in the drawing hereof. The figure forming part of the design is releasably confined to the wall by suitable connection with it, and the wall and figure thus constitute a single unitary design.

I claim:

The ornamental design for a jig-saw puzzle, as shown and described.

RICHARD B. MORRIS.
